Patented Apr. 28, 1914.

UNITED STATES PATENT OFFICE.

MABEL HARRINGTON, OF NEWARK, NEW JERSEY.

BRASSIÈRE.

1,095,109.

Specification of Letters Patent. Patented Apr. 28, 1914.

Application filed January 19, 1914. Serial No. 813,000.

To all whom it may concern:

Be it known that I, MABEL HARRINGTON, a citizen of the United States, residing at Newark, in the county of Essex and State 5 of New Jersey, have invented new and useful Improvements in Brassières, of which the following is a specification.

This invention relates to improvements in brassières, and proposes a construction 10 which is especially adapted as a bust form and is essentially useful for rectifying defects in the human figure and for producing natural bust outlines.

For this purpose the brassière is provided 15 with individually adjustable breast pads made up of circular shirr ruffles and so combined with the garment proper that they form natural and rounded bust outlines, yet are essentially inconspicuous and incapable 20 of detection. Such a brassière may be used with especial advantage by persons whose flatness of bust may amount to a substantial deformity, or whose bust may be irregularly developed, *i. e.* larger on one side than the 25 other.

An embodiment of the invention is illustrated in the accompanying drawing, wherein:

Figure 1 is a perspective view of a 30 brassière in which the features of the invention are incorporated; Fig. 2 is a view looking toward the inner face of the front of the improved brassière; and Fig. 3 is a detail sectional view of one of the breast pads on the line 3—3 of Fig. 2.

Similar characters of reference designate corresponding parts throughout the several views.

The brassière consists of a form fitting 40 upper garment 1 of any suitable construction and provided with breast pads designated generally by the numeral 2. The breast pads 2 are arranged adjacent the inner face of the garment and are permanently associated therewith. The section or 45 sections of material forming the front of the garment have their external surface perfectly plain and smooth, and are so shaped as to provide some fullness at each side of 50 the garment, which fullness is taken up by the breast pads 2 which intervene between the garment proper and the wearer's body.

The breast pads are of circular form and

in each instance comprise a circular retaining strip 3, permanently secured along a 55 circular line to the garment 1 and having at its free edge a draw string 4, and a plurality of overlapping or concentric circular ruffled padding strips 5 arranged within the strips 3 and having their ruffles in nested relation. The strips 5, as shown and preferred, are made of an integral section of material and are provided by folding said material along circular lines. The strips 5 are permanently secured to the garment 65 along a circular line concentric and closely adjacent the line of attachment of the strip 3.

The pads 2 may be adjusted to have any suitable or desired thickness. As the draw 70 string 4 is tightened, the thickness of the pad provided by the strips 5 is diminished. On the other hand, if the draw string 4 be "let out", the strips 3 and 5 can assume a greater angle relatively to the garment and 75 the strips 5 will also have a measure of expansion, so that the thickness of the pad is correspondingly increased. It will be observed that in any event the pad as a whole has a meniscus cross section, being of least 80 thickness adjacent the edges of the strips 4 and 5 and that, whatever its adjustment, the external surface of the garment is perfectly smooth and regular, yet presents a clearly defined outline similar to that of 85 any form fitting upper garment when worn on a normal figure.

Having fully described my invention, I claim:

1. A brassière comprising a form fitting 90 upper garment having breast pads at each side of the front thereof, each breast pad comprising a circular retaining strip secured by stitching along a circular line to the inner face of the garment, and having 95 a draw string along its inner free edge, and a plurality of ruffled circular padding strips arranged concentrically within the retaining strip and also secured by stitching along a circular line to the inner face of the garment, the line of attachment of the padding strips closely adjoining the line of attachment of the retaining strip. 100

2. A brassière comprising a form fitting upper garment having breast pads at each 105 side of the front thereof, each breast pad

comprising a circular retaining strip secured by stitching along a circular line to the inner face of the garment, and having a draw string along its inner free edge, and 5 a plurality of ruffled circular padding strips arranged concentrically within the retaining strip.

In testimony whereof I have hereunto set my hand in presence of two subscribing witnesses.

MABEL HARRINGTON.

Witnesses:

S. D. BUCHANAN,
F. W. KREPS.
